SUIT BOX

Octavia E. Phillips, Santa Clara, Calif.

Application September 15, 1934, Serial No. 744,182

5 Claims. (Cl. 206—7)

The invention relates to a carton or box for enclosing the garments of a suit of clothing for the protection and transportation thereof.

An object of the invention is to provide an improved suit box of the class described by shaping it from a single blank of cardboard or the like to provide a complete enclosure for the garments therein.

Another object is to provide for fixing the contents of the shaped box in place therein solely by means integral with the box structure and in such manner that the garments in the box are held in place and as originally disposed even though the box may be disposed on an edge thereof or be roughly handled.

A further object is to provide a generally improved suit box structure which provides coat and pants hanger facilities.

The invention possesses other objects and features of advantage, some of which, with the foregoing, will be set forth or be apparent in the following description of a preferred embodiment thereof, and in the accompanying drawings, in which,

25 Figure 1 shows a box embodying the features of present invention partly folded and with hanger members thereof in position for the mounting of garments thereon.

30 Figure 2 is a perspective view of the completely folded box.

Figure 3 is a fragmentary top view of a corner of the box, top portions of the structure being broken away to show the side wall relations thereunder.

35 Figure 4 is an inside face view of the flat blank from which the present box is adapted to be shaped.

Figure 5 is an enlarged longitudinal section through the folded box and showing garments disposed and held therein.

40 Figure 6 is a transverse section at 6—6 in Figure 5.

As particularly illustrated in Figures 1 and 4, the suit box of my invention is adapted to be shaped from a unitary and generally rectangular blank 8 of sheet material which is suitably cut and scored to define various sections which comprise wall and hanger and securing portions of the formed box 9. The scoring for bending at mutually coterminous sections may be of a nature suitable to the material used for the blank, said blank being economically formed of cardboard or the like; each line of scoring is preferably provided at the face of the blank which is to provide the inside of a corner defined by a

bend at the score line. In the drawings, the various score lines are indicated by dash lines.

The box proper comprises a rectangular bottom section 11 bounded by rectangular side sections 12 and 13 and end sections 14 and 15 all of like width, cover sections 16 and 17 respectively extending from the front edges of the side sections 12 and 13, and square corner sections 18. The cover section 17 is of substantially the same width as the bottom section 11 and is arranged to be overlapped along its outer longitudinal edge by the relatively narrow cover section 16 in the manner shown in Figures 2 and 6. Preferably, and as shown, diagonal slots 21 are provided in the cover section 17 adjacent its free longitudinal edge, and the section 16 is formed with lateral tongues 22 at its ends for engagement in the slots 21 to interlock the cover sections and keep the box in closed condition. For descriptive convenience, corresponding blank and box portions are herein numbered alike.

It will now be noted that the corner sections 18 are each coterminous with a side and end section thereat and are diagonally scored whereby they may be bent at the diagonal score lines as the side and end sections are disposed in perpendicular relation to the bottom section 11 in shaping the box from the blank. The arrangement is understood to provide for the disposal of the two triangular portions of each corner section within the box interior, with the free section edges engaging the top structure of the box whereby the box corners are stiffened and reinforced against crushing; the arrangement is also understood to provide sealed corners for the box. Since the registering ends of mutually coterminous box sides and ends are not positively secured together in fixed relation, it will be understood that the present structure is in the nature of a wrapper, since it may be opened out flat merely by disengaging the interlocking means of the cover sections 16 and 17 which constitute the sole means of the box for maintaining its form as a box.

A coat-and-pants hanger 23 extends from the outer edge of the end section 14, said hanger comprising a flap attached at the neck end of the hanger and being arranged for engagement in and across the shoulder portions of an upper garment C. A slot 24 is provided across the flap 23 for the passage of the legs of a pair of trousers P therethrough whereby the pants may be looped back on themselves at the slot in a usual manner and while disposed longitudinal-

ly of the garment C. Preferably, and as shown in Figures 1 and 5 and 6, the slot 24 is provided by bending a rectangular portion 25 transversely outwardly from the flap at the lower slot edge 5 whereby the slot opening is defined and the portion 25 provides a widened edge at the loop in the trouser legs and a cross-creasing of the legs thereat is avoided. The portion 25 is also understood to provide a stiffening flange across the 10 hanger, and is further utilized in a manner to be hereinafter brought out.

Flaps 26 extend from the outer edge of the end section 14 at opposite sides of the flap 23. For a reason to be hereinafter brought out, the 15 flaps 26 are separated from the hanger flap 23 solely by the cuts which define the boundaries of the latter flap. Preferably, and as shown, the flaps 23 and 26 together define a rectangular area which comprises an extension of the end section 14 and has the same width as the bottom section 11. The arrangement is such that when an upper garment C is mounted on the hanger 23, the subsequent swinging of the flaps 26 toward the plane of the hanger and about 20 the common axis of attachment of the hanger and flaps will pinch the garment between these elements at their mutually opposed edges and thereby secure the portions of the garment at its shoulders against lateral displacement on the hanger; this coaction of the hanger and flaps is brought out in Figure 6. It will be noted that the cover element 17 is operative to hold the flaps 26 in operative position against the garment C on the hanger when the box is closed.

Means are provided for securing the garment portions adjacent the box end 15 against lateral displacement. As particularly disclosed, said means comprises an extension of the end wall 15 to provide elements 27 and 28 in series relation with said wall, with the element hingedly related to the wall 15 at its front edge line and the element 28 hingedly related to the element 27 at a line which is parallel to said front edge line of the wall 15. The elements 27 and 28 are 45 both rectangular and preferably extend for the full width of the box. The element 27 has a length approximating the depth of the folded box and is arranged to have its free end edge 29 engaged with and across garment portions adjacent the box end 15 while it is disposed transverse to the plane of said garments. The 50 length of the element 27 is such as will provide for an operative disposal of the element adjacent the box end 15.

When the cover element 17 is secured in its place, it is arranged to engage the element 28 along its hinged edge for pressing the element edge 29 against the garments beneath it and with said element extending obliquely toward the plane of the box end 15 whereby the clothing therebeneath is urged toward said end; the relation is specifically indicated in Figure 5. It will be understood that any tendency of the garment to shift toward the hanger end of the box will be positively resisted by the action of the element 28 against the garment and that the hanger 23 and the element are mutually cooperative to keep the garments in the box longitudinally stretched. While such is not shown, it will be obvious that the edge 29 might be more or less toothed to increase its frictional engagement with the clothing; in any event, the garment is frictionally engaged by the element 28 against lateral shifting beneath the edge 29.

As particularly illustrated, the cover section

17 is also provided with a garment hanger means, said means comprising a hanger flap 31 extending integrally from the cover end adjacent the end wall 14. Shoulder clamp flaps 32 are provided at opposite sides of the hanger 31, and the present hanger and flaps are defined in a rectangular extension of the blank 3 and are arranged to cooperate as the previously described hanger 23 and flaps 26. In the present instance, however, the pants-receiving opening 33 lacks the flanged edge structure of the opening 24 and the hanger is provided at its free end with a relatively narrow flange portion 34 which is disposed in more or less perpendicular relation to the plane of the hanger and extends upwardly 15 from the cover 17 when the hanger overlies the cover. At its other end, the cover section 17 is provided with a flat and rectangular extension 35 which may be folded over garments D mounted on the hanger 31 and disposed against 20 the inside face of the cover section 17; in this manner, the operative disposal of the cover section 17 over the bottom section 11 while both sections have clothing mounted thereon and thereagainst is greatly facilitated.

It will now be noted that in packaging garments in the present box structure, the box blank 8 is first laid out flat and the hangers 23 and 31 are folded over to positions opposite the bottom element 11 and the cover 17 respectively, as shown in Figure 1, for the mounting of garments thereon. When the garments are mounted on the respective hangers they are smoothed out against the bottom and cover in unwrinkled condition. For minimizing folding, the box length is preferably such that the coats or the like on the hangers need not be doubled back at their lower ends; under these circumstances, pants mounted on a hanger 23 or 31 need have but one intermediate fold in their length and at the hanger slot which receives them. Generally speaking, the hanger 23 is arranged to mount heavier clothing than the hanger 31.

Having the garments mounted and disposed as described, the holding element 28 is operatively engaged with the garments on the hanger 23 and the flap 35 is folded against the garments on the hanger 31. The packed bottom and cover sections of the box are now folded together and the packaging is completed by engaging the tongues 22 of the cover element 17 with the slots 21 of the cover element 17. When garments are to be removed, the described packaging steps are effected in the reverse order.

By reference to Figure 5, it will be particularly noted that the packaged garments on the two hangers become positioned intermediately in the space between the box bottom and cover. Furthermore, the flanges 25 and 34 of the hangers 23 and 31 are operative in different planes and oppositely on the garment portions between them to further secure the garments thereat. At the opposite end of the box, the holder element 28 engages against the flap element 35 whereby each of these elements is operative to hold the other in operative relation to the garments which it engages.

It will be understood that the hanger and flap on the cover 17 may be omitted from the present structure without sacrificing certain noted advantages of the disclosed arrangement. Also, the present box, when made of cardboard of a usual thickness for such boxes, is particularly stiff against crushing, particularly at its

corners, and is therefore especially adapted for transportation by hand or mail or express.

If desired, a knock-out area 37 may be provided in the bottom element 11 adjacent and 5 behind the hanger 23 whereby the package is arranged to be hung on a wall hook after it reaches its destination and either before or after opening. Furthermore, the standing of the closed box on any edge thereof does not permit a 10 wrinkling of its contents by reason of any shifting of the garments therein; if the box is to be so positioned for some time, it should preferably stand on the end 15, however, since this would dispose the hangers in normal operative 15 positions thereof.

From the foregoing description taken in connection with the accompanying drawings, the advantages of the construction and method of operation will be readily understood by those skilled in the art to which the invention appertains. While I have described the features and the use of the device which I now consider to be a preferred embodiment of my invention, I desire to have it understood that the showing is 20 primarily illustrative, and that such changes 25 may be made as fall within the scope of the following claims.

I claim:—

1. A one-piece suit box having a bottom wall 30 and side walls and end walls, a suit hanger flap extending integrally from the top edge of a said wall and laterally shaped for engagement in the shoulder-receiving portions of an upper garment and provided with a pants-receiving slot there-across, and an integral flange extending from the lower slot edge and transversely from the plane of the flap.

2. A one-piece suit box having a bottom wall and end walls, a suit hanger flap extending integrally from the front edge of a said end wall 40 and laterally shaped for engagement in the shoulder-receiving portions of an upper garment, securing flaps extending integrally from said wall edge at opposite sides of the hanger flap and having edges thereof cooperative with the

opposed side edge portions of the hanger flap for gripping a garment on the latter at the shoulder line of the garment, and a securing flap extending integrally from the opposite end wall from that first mentioned and arranged for engagement against the lower garment end to secure the same against the bottom wall thereat.

3. In a suit box formed of sheet material and having a bottom wall and side and/or end walls, 10 a suit hanger extending integrally from the edge of a said wall and laterally shaped for engagement in the shoulder-receiving portions of an upper garment, and a flap extending integrally from the wall opposite that from which 15 the suit hanger extends and providing a planar portion for disposal across a lower part of a garment extending from said hanger for securing the garment against the bottom wall thereat, said portion being arranged to engage 20 said garment in a manner to maintain it stretched from said hanger.

4. In a suit box formed of sheet material and having a bottom wall and side walls and end walls, a suit hanger extending integrally from 25 the front edge of an end wall and laterally shaped for engagement in the upper portions of an upper garment, a flap extending integrally from the front edge of the other end wall and providing a planar end portion for disposal 30 transversely against a lower portion of a garment extending from said hanger for securing the garment against the bottom wall thereat, and a cover element for the box extending integrally from the front edge of a said side wall 35 of the box and arranged to dispose and retain the securing portion of said flap in operative position when the box is closed therewith.

5. A structure in accordance with claim 4 40 characterized by the provision of means including a hanger integral with the cover element for securing a garment on the element at its inner face.

OCTAVIA E. PHILLIPS.
